UNITED STATES PATENT OFFICE.

KARL ALQUIST, OF SCHENECTADY, NEW YORK, ASSIGNOR TO GENERAL ELECTRIC COMPANY, A CORPORATION OF NEW YORK.

MARINE TURBINE.

1,190,074.

Specification of Letters Patent.

Patented July 4, 1916.

Application filed April 27, 1916. Serial No. 94,081.

To all whom it may concern:

Be it known that I, KARL ALQUIST, a subject of the King of Sweden, residing at Schenectady, in the county of Schenectady, State 5 of New York, have invented certain new and useful Improvements in Marine Turbines, of which the following is a specification.

The present invention relates to marine turbines for propelling vessels, and in particular to vessels which are required to operate at different times at widely different speeds. Such a condition is found, for example, in war vessels which for the greater part of the time, are operated at cruising 15 speed, but at times are required to operate at higher or maximum speeds.

The object of the present invention is to provide an improved arrangement and grouping of turbines on a vessel which will 20 be economical to build and install and which will give a high efficiency, not only at cruising speed, but also at maximum speed, and at various speeds between cruising speed and maximum speed.

25 For a consideration of what I believe to be novel and my invention, attention is directed to the accompanying specification and the claims appended thereto.

In the accompanying drawing the figure 30 is a diagrammatic plan view of an installation embodying my invention, the same being shown in connection with a twin-screw system of propulsion.

2 and 3 indicate twin main turbines for 35 propelling the vessel at maximum speed, each of which drives a propeller shaft 4 either directly or through speed reducing gearing 5. The latter arrangement is preferable because the propeller 6 can be driven 40 at its most favorable effective speed, while the turbine can be made relatively small and light and operated at a high and most favorable speed, thereby obtaining good economy of operation. By arranging the gearing 45 in the position shown it is always in service whether the ship is being driven at full, intermediate, or cruising speed. I have not illustrated the gearing in detail because its specific construction forms no part of the 50 present invention. The turbines operate on the impulse plan and are preferably of the Curtis type because of their high economy and decreased weight and moderate speed for a given output. Each turbine has a forward driving element 7, comprising, in the

present instance, one or more wheels 8 having a plurality of rows of peripheral buckets and one or more wheels 9, each having a single row of peripheral buckets, said wheels being mounted on the shaft 10. In the rear 60 end of each turbine casing is located a reversing element 11, comprising one or more bucket wheels mounted on the shaft 10. Both the forward driving and reversing elements exhaust through exhaust opening 12 65 to a condenser (not shown).

The extracting capacity of turbine buckets depends roughly on the square of their speed. That is to say, if the bucket speed be decreased one-half, the energy range for 70 equal extracting efficiency thereof will be reduced to about one-fourth, hence the importance of increasing the number of stages for reduced speed operation, a feature which will be referred to later.

75 Each main turbine is provided with a set of nozzles 13 adapted in size and shape to receive high pressure boiler steam from the supply main 14 and convert a predetermined percentage of its pressure into velocity, 80

which in turn is converted into useful work by the rotating element, as is well understood. Between the various bucket wheels, each in a stage of its own, are stage nozzles 15 for converting pressure into velocity and 85

conveying steam between the stages in a manner well understood. Each turbine may also be provided with an auxiliary or low pressure set of nozzles 16 adapted in shape 90

and size to receive exhaust steam from a cruising turbine, to be described later, and convert a predetermined percentage of its pressure into velocity, which in turn is converted into useful work by the rotating element. The main and auxiliary nozzles 95

receive their supplies of steam from separate chests, the purpose of which will be referred to later. When operating at full speed and power the auxiliary set of nozzles 16 in each main turbine is cut out of service. They are, 100

however, in service for cruising speed conditions. For full and high intermediate speed conditions the main admission nozzles only 105

are in service. The main turbines are designed to give their maximum economy at nearly full or full speed of the ship.

Situated in line with the main turbines, and preferably forward thereof to facilitate cutting the same into and out of service, are auxiliary or cruising turbines 17 and 110

18 that are adapted to be connected to and disconnected from the main turbine shafts by releasable clutch couplings 19 and 20. These turbines are provided with bucket 5 wheels of such diameter as to efficiently extract energy from the steam at lower speeds of the ship. They may be uncoupled from the main turbines when the latter are operating at high speed, or they may have their 10 casings connected to a condenser, or other region of lower pressure so as to avoid the rotation losses due to the rotation of the wheels within their casings. By uncoupling the cruising turbines when driving the vessel at highest speeds, I can make their bucket 15 speeds somewhat higher than would otherwise be possible, though it is generally desirable to have the bucket strong enough to withstand the highest speed they would reach 20 if the turbines were not disconnected. The cruising turbine 17 has high pressure admission nozzles 21 adapted to convert a predetermined percentage of pressure into velocity which in turn is extracted by the buckets of the rotor. The exhaust opening of 25 cruising turbines 17 is connected by way of conduit 22 to the admission nozzles 23 of the cruising turbine 18, which nozzles are designed to properly handle lower pressure 30 steam, and the exhaust opening of cruising turbine 18 is connected by way of conduit 24 and branch conduits 25 and 26 to the low pressure nozzles 16 of the main turbines 2 and 13. Arranged in the conduits 25 and 35 26 are suitable non-return valves 25^a and 26^a which prevent steam from flowing from the main turbines back into the cruising turbines when the main turbines are propelling the ship and the cruising turbines are idle. The 40 high pressure nozzles 18 of the main turbines are connected to the supply main 14 by conduits 27 and 28 and the reversing elements 11 are connected thereto by conduits 29 and 30. The high pressure nozzles 21 of 45 cruising turbine 17 are connected to the supply main 14 by conduit 51. In each of the conduits 27, 28, 29, 30 and 31, are suitable valves 27^a, 28^a, 29^a, 30^a and 31^a for controlling the flow through them. In connection 50 with the cruising turbine 17 is provided a by-pass conduit 32 which is connected at one end to the exhaust conduit 22 and has branches 33 and 34 which connect with the 55 cruising turbine at two spaced intermediate points. It is provided with valves 35 and 36. By opening one or both of these valves lower stages of the cruising turbine 17 can be by-passed, as will be explained more fully hereinafter. Also the cruising turbine 18 is 60 provided with a by-pass conduit 37 having a valve 38 therein. By opening this valve a number of the first stages of cruising turbine 18 can be by-passed.

39 is a pipe which is provided with a valve 65 40 and which connects the conduit 24 to the

exhaust end of one of the main turbines, in the present instance main turbine 2. When the auxiliary turbines 17 and 18 are running idle the valve 40 is opened and the non-return valves 25^a and 26^a closed. This will 70 connect the casings of the cruising turbines to the condenser of the main turbine or turbines so that the wheels of the cruising turbines will then be operating in a medium of very low pressure. 75

The operation is as follows: When the vessel is to be propelled at maximum speed the valves 27^a and 28^a are opened to admit live steam directly to the nozzles 13 of the main turbines. At this time the cruising 80 turbines may be uncoupled at 19 and 20, or they may be left coupled and connected to a condenser or other region of lower pressure by opening the valve 40 as already explained. The main turbines then operate to 85 propel the vessel at its maximum speed. For reverse operation, the valves 27^a and 28^a are closed and the valves 29^a and 30^a opened. This admits live steam to the reversing elements 11 to propel the vessel in a reverse 90 direction as is well understood. When it is desired to propel the vessel at cruising speed the valves 27^a, 28^a, 29^a and 30^a are closed and the valves 25, 26, and 31^a are opened. This will admit live steam to the nozzles 21 of 95 the cruising turbine 17. If the lowest cruising speed is desired the valves 35, 36 and 38 are kept closed. The steam then passes through all the stages of the cruising turbine 17 thence by way of conduit 22 to the nozzles 23 of cruising turbine 18. It then passes 100 through all the stages of cruising turbine 18, after which it passes through conduit 24 to the branch conduits 25 and 26, and thence to the low pressure nozzles 16 of the main 105 turbines 2 and 3. The separate auxiliary nozzles 16 of the main turbines are provided so as to avoid the possibility of live steam getting back to the casings of the 110 cruising turbines. If the same nozzles were used in the main turbines for boiler steam and also exhaust steam from the cruising turbine, whenever the boiler steam was admitted to the chest supplying said nozzles, it 115 might find its way past the non-return valves 25^a and 26^a back to the casings of the cruising turbines.

With the arrangement for cruising as just described, all the wheels of both the 120 cruising turbines and the main turbines are in service so that the lowest speed of the propeller shafts is obtained. If now a slightly higher speed is desired, the valve 35, for example, is opened so as to by-pass the last stages of the cruising turbine 16. 125 This cuts a number of wheels of said cruising turbine out of action, in the present instance 3, so that a higher speed may now be efficiently obtained. Instead of opening the valve 35 the valve 38 might be opened, 130

thus by-passing a number of the first stages of the cruising turbine 18. It will be understood that the steam will flow around these stages because in any instance, it will take the path of least resistance. If a still higher intermediate speed is desired then the valves 35 and 38 may both be opened, thereby by-passing the latter stages of the cruising turbine 17 and the first stages of the cruising turbine 18, and if a still higher speed is desired then the valve 36 may also be opened thus by-passing still more stages of the cruising turbine 17. As will be understood, any degree of refinement may be provided in connection with the by-passing of stages of the two cruising turbines. In the simplest form for example, I may provide only a single by-pass in connection with one of the cruising turbines. This would give then one efficient intermediate speed which may in many cases be sufficient, or I may provide one by-pass in connection with each of the cruising turbines, or more than one, as may be found desirable.

25 The above described arrangement has the advantage that the cruising turbines need be provided with but one set of admission nozzles and these may be designed for the most efficient operation at the pressures for which 30 they are to be used; *i. e.* the cruising turbine 17 has a single set of high pressure admission nozzles 21, while the cruising turbine 18 has a single set of low pressure admission nozzles 23. By this arrangement I 35 can also have complete peripheral admission for the elastic fluid for each of the cruising turbines so that all the buckets of the wheels are in action all the time.

In accordance with the provisions of the 40 patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—
50 1. In a system of ship propulsion, the combination of main turbines arranged to propel the ship at maximum speed, cruising turbines arranged to coöperate with the main turbines to propel the ship at speeds 55 below the maximum, means for connecting the cruising turbines in series with each other as regards the flow of steam and to

supply the exhaust therefrom in parallel to the main turbines for lower speeds of the ship, and means for by-passing one or more 60 stages of a cruising turbine for speeds between the maximum and the lower speeds.

2. In a system of ship propulsion, the combination of main turbines arranged to propel the ship at maximum speed, main and auxiliary nozzles for the turbines, the former being adapted in size and shape to receive live steam and the latter exhaust steam, cruising turbines arranged to co-operate with the main turbines to propel the 70 ship at speeds below the maximum, means arranged to connect the cruising turbines serially as regards the flow of steam and to supply the exhaust therefrom to the auxiliary nozzles of the main turbines in parallel 75 for lower speeds of the ship, and means for by-passing one or more stages of a cruising turbine for speeds between the maximum and the lower speeds.

3. In a system of ship propulsion, the combination of main turbines arranged to propel the ship at maximum speed, cruising turbines arranged to coöperate with the main turbines to propel the ship at speeds below the maximum, means for connecting 85 the cruising turbines in series with each other as regards the flow of steam and to supply the exhaust therefrom in parallel to the main turbines for lower speeds of the ship, means for by-passing one or more 90 stages of a cruising turbine for speeds between the maximum and the lower speeds, and means for connecting the casings of the cruising turbines to a region of lower pressure when the ship is running with the 95 cruising turbines idle.

4. In a system of ship propulsion, the combination of main turbines arranged to propel the ship at maximum speed, cruising turbines arranged to coöperate with the 100 main turbines to propel the ship at speeds below the maximum, means for connecting the cruising turbines in series with each other as regards the flow of steam and to supply the exhaust therefrom in parallel 105 to the main turbines for lower speeds of the ship, and by-passing conduits in connection with each of the cruising turbines for shunting elastic fluid around one or more stages of such turbines for intermediate speeds of 110 the ship.

In witness whereof, I have hereunto set my hand this 26th day of April 1916.

KARL ALQUIST.
